UNITED STATES PATENT OFFICE.

ATKIN M. INGRAM, OF MONTGOMERY, ALABAMA, ASSIGNOR OF ONE-HALF TO WILLIAM J. GARDNER, OF MONTGOMERY, ALABAMA.

CHECK-VALVE.

1,039,749.

Specification of Letters Patent.

Patented Oct. 1, 1912.

Application filed June 16, 1910. Serial No. 567,309.

To all whom it may concern:

Be it known that I, ATKIN M. INGRAM, a citizen of the United States, and a resident of Montgomery, in the county of Montgomery and State of Alabama, have invented certain new and useful Improvements in Check-Valves, of which the following is a full and clear specification, reference being had to the accompanying drawings, in 10 which—

Figure 1 is a vertical section of the valve structure complete; and Fig. 2 an elevation of the upper half of the inner side of the removable valve carrying head or flange.

15 This valve structure is especially designed for use with heavy acids, especially sulfuric and other vitriolic liquid bodies, it being especially designed to be placed in the pipe line between the storage tank and a receptacle known as an egg, from which egg the acid is pumped or forced by air pressure; and the object of this invention is to render the valve self-opening as well as self-closing and to improve its general structure, 20 as more fully hereinafter set forth.

The valve casing *a* is made any suitable shape and area and is provided with an outlet *b* for the liquid and inlet *c* for air when the valve is to be used with an air forcing 30 means. The front end of the casing is closed by a head *d* which is clamped rigidly to the casing by suitable bolts, the joint being rendered non-leakable by rabbeting the inner annular corner of the valve casing at *e* to 35 receive a similarly shaped annular shoulder *f* on the head. With a joint of this construction, if the contacting surfaces are fitted and dressed nicely, packing material is rendered unnecessary.

40 The inlet *g* extends through the center of the head, and around the inlet on the inner face of the head is formed an annular flange *h* which serves as the valve seat. The seating-surface of this valve seat is in two parts, 45 namely, the annular beveled portion *i* and the annular flat face *j*. The valve plate *k* pivotally depends from a pair of lugs *l* projecting inwardly from the head *d* at points above the valve seat, these lugs being arranged upon opposite sides of a vertical line 50 drawn through the center of the valve seat and being adapted to receive the lateral pivots or trunnions *m* of the valve plate.

The trunnions or pivots rest in notches *n*

formed in the upper edges of the supporting lugs, the trunnions being confined in the notches by the valve casing when the head is bolted thereto. When the head is removed from the valve casing it will be observed that the valve plate may be lifted out of the supporting lugs to enable the parts to be cleaned and repaired. The valve plate is pivoted at a point back of the valve seat so that when there is no pressure in the valve casing the valve plate will normally swing 65 away from the valve seat, the valve being thereby kept normally open. The notches *n* are elongated sufficiently to permit the trunnions to have a bodily movement forward and backward therein so that when the valve 70 is permitted to open it will move a certain distance bodily away from the valve seat and thus permit the free passage of the liquid, this being especially advantageous when the valve is used with heavy liquids such as 75 sulfuric and nitrous acids.

The pivoting of the valve plate at a point back of the valve seat causes the valve plate to assume a position inclined upwardly and backwardly when it is forced to its seat, as 80 shown in dotted lines in Fig. 1. This necessitates the inclining of the double valve seat *i*—*j* in the same direction so that the corresponding seating surfaces *o*—*p* on the valve plate shall seat properly when the valve is 85 closed. This provision of a double seating surface, one inclined with respect to the other renders the valve non-leakable. This idea of inclining the valve seat upwardly and inwardly and the making of the lower 90 portion of the beveled portion *i* of the valve seat shorter or narrower, has an important advantageous result when the valve is used with heavy liquids in that it permits the 95 free and quick passage of any solid or foreign matters that may be carried into the valve along with the acids, and this free flow of the liquids is still further promoted by the fact that the valve remains wide open when not under pressure of the air. 100

I prefer constructing the valve throughout, except the bolts and nuts, of an alloy of lead and antimony, in order to render it non-corrodible. It will be observed that a further advantage of my valve structure is 105 that I avoid all pockets and crevices that might form pockets for the lodgment of foreign substances.

Having thus fully described my invention, what I claim as new, and desire to secure by Letters Patent, is—

The combination of a valve casing having a horizontal inlet having an annular valve seat projecting therefrom into the casing, said valve seat inclining upwardly and inwardly, a pivot support located within the casing at a point above the valve seat, a valve plate having trunnions hung in said support and adapted to freely swing therein to and from the said valve seat, the axis of its trunnions being located above and beyond the valve seat so that the valve plate shall nor-

mally swing bodily away from the valve seat, 15 said support for the pivots being enlarged inwardly in a direction away from the valve seat to permit said trunnions to have a movement toward and from the seat simultaneously with the movement of the valve plate 20 respectively toward and from the seat.

In testimony whereof I hereunto affix my signature in the presence of two witnesses this 14 day of June 1910.

ATKIN M. INGRAM.
